WILLIAM EBEN HOKE, OF BALTIMORE, MARYLAND, ASSIGNOR TO JOSEPH MERCANTE, OF NEW YORK, N. Y.

ROTARY PUMP

Application filed May 20, 1927. Serial No. 192,850.

This invention relates to rotary pumps of the general type disclosed in the Groh Patent No. 1,495,411, issued May 27, 1924, and it includes not only improvements in pumps of this character, but also improvements in gears suitable for use in rotary pumps and improvements in methods of making such gears.

Rotary pumps of the character described in the said Patent No. 1,495,411 comprise a pump chamber casing enclosing intermeshing gears. In the operation of the pump, the fluid being pumped or compressed enters the spaces between the gear teeth as they disengage and the fluid is discharged from these spaces into the high pressure side of the system. As the gear teeth come into mesh, all of the fluid occupying the tooth spaces with the exception of the clearance spaces is expelled, and where a gas is being pumped, a suitable cooling fluid such as oil is relied upon to prevent communication between the high and low pressure sides of the pump system through the clearance spaces. A considerable quantity of sealing fluid is ordinarily employed for this purpose, and even at best there is some leakage of the pumped fluid from the high pressure side of the system to the low pressure side. The use of a considerable quantity of sealing fluid presents a number of difficulties which have heretofore been considered unavoidable. The normal action of the pump causes the sealing fluid to foam, and various attempts have been made to preserve the quality of the sealing fluid, as by cooling the same. Furthermore, it is very difficult, if not impossible, to prevent some of the sealing fluid from becoming so intimately associated with the pumped fluid as to render the separation of these materials impossible except by the use of special apparatus designed for this purpose.

One of the objects of my invention is to provide a rotary pump in which it is unnecessary to use the usual quantity of sealing fluid, it being necessary to merely employ enough oil to lubricate the parts. A further object of this invention is to provide a rotary pump of higher efficiency than those heretofore used, and this by virtue of the fact that gears of an improved character are employed, the gears

being constructed in such a manner that there is substantially no clearance between the intermeshing teeth.

A further object of my invention is to provide a gear pump having an inlet port extending substantially to the center line, passing through the axes of the gears, whereby the enlarging tooth spaces remain in communication with the fluid supply until the spaces are entirely filled. 55

A further object is to provide a rotary pump having spirally cut gears and a discharge or relief port extending substantially to the vertical center line passing through the axes of the gears, to thereby prevent trapping of liquid between intermeshing teeth as they come together. This prevents the hammering action ordinarily encountered with pumps of this type, and renders the operation of the pump noiseless. Still another object of my invention is to provide gears for rotary pumps having teeth, the profiles and root outlines of which comprise a continuous development or generation of the gear tooth curve, and as stated above, my invention includes an improved method of making the gears just described. 60 65 70 75

My improved method includes the use of a reversibly symmetrical rack-like cutter for forming the improved gears, the gears being formed in such a manner that no appreciable clearance space is provided. It will be understood, however, that gears of the improved type can be made by the use of means other than this particular form of gear cutter. 80 85

The various objects and advantages of my invention will be more apparent upon considering the following detailed description, which is to be taken in conjunction with the accompanying drawings, in which I have illustrated certain embodiments of my invention. In the accompanying drawings, 90

Fig. 1 is an enlarged fragmentary view of two intermeshing gears made in accordance with my invention; 95

Fig. 2 is an enlarged fragmentary view of one of the improved gears and a cutter suitable for making the gear;

Figs. 3 and 4 are enlarged fragmentary views of other forms of gear cutters; 100

Fig. 5 is a vertical section view taken on line 5—5 of Fig. 7;

Fig. 6 is a transverse section view taken on line 6—6 of Fig. 5, showing details of construction;

Fig. 7 is a transverse section view taken on line 7—7 of Fig. 5, showing details of construction;

Fig. 8 is an end elevation of the pump shown in Fig. 5;

Fig. 9 is a transverse section view taken on line 9—9 of Fig. 5, showing details of construction;

Fig. 10 is a transverse section view taken on line 10—10 of Fig. 5, showing the construction of the pump casing;

Fig. 11 is a transverse section view taken on line 11—11 of Fig. 5, showing details of construction; and

Figs. 12 and 13 are perspective views of a spirally cut gear made in accordance with my invention.

The accompanying illustrations of certain embodiments of my invention show gears having teeth the profiles and root outlines of which comprise the continuous development of a gear tooth curve, one of the characteristics of the gears being that the crowns of the teeth of one gear are adapted to "bottom" or make contact with the corresponding root portions of the gear intermeshing therewith. In other words, the gear teeth are so shaped that all portions thereof, from the lowest points of the roots to the highest points of the crowns, cooperate in gear action during the rotation of the intermeshing gears. In ordinary gears, the root circle, which bounds the bottoms of the tooth roots, is lower than the working depth circle or the circle bounding the extent to which a tooth crown on a cooperating gear enters a tooth root. Thus the portions of ordinary gear teeth below the working depth circles, as well as the portions of the crowns tangent to the addendum circle, do not cooperate in gear action because they do not follow developments of any gear-tooth curve. In the gears of the present invention, the root circles and working depth circles are coincident, the tooth profiles and root outlines being continuous developments of a gear tooth curve throughout. Thus gear action takes place over the entire surface of each gear tooth during the rotation of the cooperating gears.

The gears of the present invention are preferably formed to engage without back-lash, that is, the thickness of each tooth is equal to the tooth space into which it meshes when measured on the pitch circle.

In Fig. 1, for example, I have illustrated a gear A, meshing with the gear B, and the tooth profiles 1 and the root outlines 2 of gear A are continuous developments or generations of the gear tooth curve. The same is true of the tooth profiles 3 and the root out-

lines 4 of gear B. In the particular gears illustrated, the gear teeth are pointed and the crowns of the teeth on one gear are adapted to engage the root surfaces of the gear meshing therewith, as illustrated at 5.

Gear teeth of the form shown in Fig. 1 can be made by utilizing a reversibly symmetrical rack-like cutter having sharp pointed teeth. The teeth and spaces of the rack are equal and symmetrical, or in other words, each tooth and the adjacent space are bounded by similar and equal lines of alternating reversion. It may be stated that if two racks of this character be fitted together, the teeth of one will exactly fit and fill the spaces of the other. One is the complement of the other, and the teeth and spaces will be exactly equal as measured on the pitch line. Gears cut by means of such a rack cutter are conjugate to the rack and to each other, and inasmuch as no clearance is provided, each tooth is adapted to make contact at a plurality of points with the intermeshing gear.

For example, one of the teeth of gear B in Fig. 1 is shown making contact with gear A at 5, 7 and 8. The gears are shown in the preferred adjusted position in which there is no back-lash.

The teeth of the rack cutter may be of any desirable form, the important consideration being that the cutter should be reversibly symmetrical. In Figs. 2, 3 and 4, I have illustrated forms of teeth different from the sharp pointed teeth just described. The teeth shown in Fig. 2 are provided with straight sides 9, with a rounded crown 10, and a correspondingly rounded root portion 11. The tooth shown in Fig. 3 is provided with straight sides 9', with a flat crown 10', and a flat root portion 11'. The tooth shown in Fig. 4 is provided with curved sides 9'', with a rounded crown 10'' and correspondingly rounded root portions 11''. The involute system of tooth curves can be employed using any portion of the curve with the result that the gears have all of the advantages incident to gears having teeth of the involute type. Other standard systems may likewise be employed.

In Figs. 5 to 11 inclusive, I have illustrated one embodiment of my invention as applied to rotary pumps. In these figures, 12 represents a portion of a pump casing of any suitable form, it being understood that the pump gears 13 and 14 are enclosed within the casing, a part of which is shown at 12. The gear 14 is keyed or otherwise fixed to a shaft 15 journaled in the casing 12 and in bearing plates 16 and 17. The shaft 15 projects through the casing wall and is driven by any suitable means (not shown). Suitable packing 18 is provided around the shaft 15, in accordance with usual practice. The gear 14 meshes with gear 13 and is carried by a shaft 19 journaled in the bearing plates 16 and 17.

The bearing plates 16 and 17 are spaced apart by a segmental or arcuate housing 20 provided with curved surfaces 21 and 22 engaging the gears 13 and 14, as best shown in Fig. 6. The several parts are held in place by bolts 20' and 20'.

The fluid to be pumped is supplied to the pump through a passage 23 extending through the pump casing 12. A fluid passage 24 communicating with the passage 23 extends through the inner bearing plate 16 so as to supply the fluid directly to the tooth spaces of the gears 13 and 14. As the gear teeth disengage, the fluid is drawn into the enlarging tooth spaces until they are substantially filled with the fluid. Thereafter, the fluid is trapped in these spaces by the curved surfaces 21 and 22 of the segmental housing 20. As the advancing gear teeth leave the extreme portions of the segmental housing, the fluid is discharged into the interior of the pump casing.

I prefer to form the passage 24 in such manner that the delivery end thereof extends substantially to the center line of the pump passing through the axes of the gears 13 and 14, as best shown in Fig. 6. With this arrangement, it is possible to fill the tooth spaces completely before communication therewith is cut off by the curved portions 21 and 22 of the segmental housing 20. The gears 13 and 14 are spirally cut and of the type above described and illustrated in Figs. 1 to 4 inclusive, and 12 and 13. The pitch of the spirally cut teeth is preferably such that one pair of cooperating teeth does not become entirely disengaged until the next pair begins to come into engagement. Accordingly, there is never a through passage along the gear tooth spaces from the interior of the pump casing to the fluid supply passage 24.

In Figs. 12 and 13, I have attempted to illustrate some of the characteristics of my improved gears which render them particularly valuable as the moving elements of a rotary pump. In these two figures, which are perspective views of a spirally cut gear made in accordance with my invention, the dotted line represents the line of contact between two intermeshing gears of this form. Fig. 13 shows the gear of Fig. 12 in a slightly different position. As shown by the dotted line, the line of contact or line of seal between two intermeshing gears of this form is continuous, and in the particular instance illustrated, extends across the crowns of two adjacent teeth. With gears of ordinary construction, the line of seal or line of contact is not continuous; it is interrupted at the crowns of the interengaging teeth due to the clearance space.

With the particular gear shown in Figs. 12 and 13, the line of contact or line of seal, although continuous, is made up of a number of parts, seven parts being shown in Fig.

13 as a, b, c, d, e, f and g. Upon referring to Fig. 12, it will be noted that the portion g of the line of seal or line of contact is in alignment with the portion c, these two portions being on corresponding faces of adjacent teeth. The particular gear illustrated in Figs. 12 and 13 is of the involute form, the tooth profiles and root outlines being a continuous development or generation of the gear tooth curve. 75

Referring again to Figs. 5 to 11 inclusive, it will be noted that the inner bearing plate 16 is provided on the inner face thereof with a depression 25 communicating with a pipe 26 by means of a channel or passage 27. Lubricating or sealing fluid can be supplied to the depression 25 through the pipe 26 and where the pump is used for the purpose of compressing a gasified refrigerating medium such as sulfur dioxide, the usual sealing fluid such as oil can be supplied to the pipe 26 from the interior of the pump casing. The sealing fluid or lubricating fluid may gain access to the gears 13 and 14 through small passages 28 and 29, best shown in Figs. 7, 9 and 10. These passages communicate with those portions of the gears 7 in contact with the segmental housing 20, and the sealing fluid may serve the purpose of compressing the gaseous fluid trapped in the tooth spaces. 95

Where my invention is employed, it is not necessary to use as much sealing fluid as is ordinarily employed; it is quite sufficient to merely employ enough of the fluid to lubricate the gears. This desirable result is made possible because of the form of the gear teeth which, as pointed out above, are capable of forming a continuous line of seal from one end to the other. 100

In order that all of the liquid in the tooth spaces may be readily expelled as the gear teeth come together, I provide an exhaust port 30 in the outer bearing plate 17. This port may extend substantially to the vertical center line passing through the axes of the gears, thus permitting all of the liquid in the gear tooth spaces to be discharged, thus eliminating the trapping of any of this liquid, as is ordinarily the case in rotary pumps. It is ordinarily impossible to locate the discharge port very close to the vertical center line of the pump because in the ordinary pump this would result in the escape of the pumped fluid from the high pressure side of the system to the low pressure side through the gear tooth spaces. This discharge is eliminated by the use of gears made in accordance with my invention. 110

It is to be understood that my invention is not limited to the particular embodiments illustrated and described, but include such modifications thereof as fall within the scope of the appended claims. For example, my improved gears can be formed by using cutters other than those herein described in de- 125

tail; my invention can be applied to gears of any type, and the details of the pump mechanism can be modified and in some instances even eliminated without sacrificing all of the advantages of my invention.

5 I claim:

1. In a pump, the combination with the pump chamber casing, of intermeshing spirally cut gears, means for introducing the 10 pumped fluid into spaces between intermeshing teeth at one end of the gears, means for introducing a sealing liquid into said spaces, and means permitting escape of said liquid from between the teeth at the point where the 15 opposite end of the teeth are completely or fully intermeshed.
2. In a pump, the combination with the pump chamber casing, of intermeshing spirally cut gears, means for introducing the 20 pumped fluid into spaces between intermeshing teeth at one end of the gears, means for introducing a sealing liquid into said spaces, and means at the opposite ends of the teeth for receiving sealing liquid forced from be- 25 tween intermeshing teeth at said opposite ends, said means being located at a point where the teeth at said opposite end are fully intermeshed.
3. In a pump, the combination with the 30 pump chamber casing, of intermeshing spirally cut gears, means for introducing the pumped fluid into spaces between intermeshing teeth at one end of the gears, means for introducing a sealing liquid into said spaces, 35 and end plates enclosing the ends of the gears, the plate at the end opposite the point of admission of pumped fluid having a relief recess therein located at the point at which the adjacent ends of the teeth are fully in- 40 termeshed.
4. In a pump, the combination with the pump chamber casing, of intermeshing spirally cut gears, means for introducing the 45 pumped fluid into spaces between intermeshing teeth at one end of the gears, means for introducing a sealing liquid into said spaces, and end plates enclosing the ends of the gears, the plate at the end of the gears remote from the point of admission of the pumped fluid 50 having a duct therein extending from its exterior face to a point on its interior face in registry with the point at which the teeth fully intermesh at that end of the gears.

In testimony whereof I affix my signature.

55 WILLIAM EBEN HOKE.
